HEALTH PROMOTING MACHINE

William John Nelson, New York, N. Y.

Application November 27, 1933, Serial No. 699,934

2 Claims. (Cl. 128—24)

The invention relates to a health promoting machine, and has for its general object, the treatment of the different ailments of the joints, muscles and nerve centers of the limbs of the 5 human body, by means of twisting exercises, and without physical exertion, on the part of the patient.

An object of my invention is to readjust misplaced bones of the limbs of the human body, 10 thereby relieving any undue pressure on the different nerve-centers.

Another object of my invention is to restore muscular tonus of the human body and to keep the limb joints active.

Another object of my invention is to secure 15 normal balance and posture of the human body by restoring muscle, tendon and ligament activity.

Another object of my invention is to cause 20 circulation of the blood freely through the human system, and to stimulate the nerve system, by relieving any undue pressure on the different nerve-centers.

Another object of my invention is to provide 25 an exercising device which will simulate the twisting limb movements used in the practice of kinesitherapy.

With the above and other objects in view, the 30 invention will be hereinafter more particularly described, and the combination and arrangement of parts will be shown in the accompanying drawings and pointed out in the claims which form part of this specification.

Reference will now be had to the drawings, 35 wherein like numerals of reference designate corresponding parts throughout the several views in which:

Figure 1 is a front elevation of my limb readjusting apparatus.

Figure 2 is a cross-sectional view, the section 40 being taken as on line 2—2 in Figure 4.

Figure 3 is a rear view of the apparatus.

Figure 4 is a top view of the apparatus.

In the illustrated embodiment of the invention, the numeral 10 indicates my limb readjusting apparatus comprising a shoe 11 secured in any suitable manner to a plate 12.

The plate 12 has been rotatably mounted on a 50 spindle 13 fixed to the front wall 14 and preferably extending and secured to the rear wall 15. A drive pin 16 is secured in right angular relation to the plate 12, and extends through a circular slot 17 in the front wall 14. The drive pin 16 has been fixed to an arm 18 which is rotatably mounted on the spindle 13. A pin 19 has been secured in right angular relation with the arm 18

and in engagement with one end of a link 20. The other end of the link 20 has a right angularly extending pin 21 in engagement with a crank arm 22. The crank arm 22 has been fixed to a shaft 23 which extends out from a bearing in the rear wall 15 and has a pinion gear 24 fixed thereon. The pinion gear 24 meshes with a gear 25 which is rotatably mounted on a spindle 26 fixed in the rear wall 15.

A pulley 27 has been fastened to the gear 25 and a belt 28 has been mounted on said pulley and engages a pulley 29 on a motor 30. Rotation of the motor 30 is transmitted through the belt 28, to the gears 25 and 24 and through the crank arm 22 to the link 20 and arm 18, and finally to the plate 12. The plate 12, being rotatably mounted at its mid portion, oscillates together with the attached shoe 11 to and fro in a circular path, as defined by the circular slot 17.

As shown in Figure 1, a plurality of adjustable straps 31 have been secured to the shoe 11 and serve to secure a foot 32 of a person in the shoe. It is to be noted that the shoe 11 has been secured to the plate 12 in a substantially vertical position so as to enable the foot 32 to be strapped there- 25 to while the leg is in a horizontal position.

When the mechanism heretofore described is in operation, it will cause the foot 32 and thigh 33 strapped to the shoe to oscillate to and fro in a circular path and to simulate the twisting limb movements used in the practice of kinesitherapy. Repetition of this oscillatory movement causes readjustment or correction of misplaced bones of the foot, ankle, knee and hip of the patient's lower limb. It is to be understood 35 that the oscillatory movements take place in rapid succession and that there is a continual and rapid reversal of the motions of the lower limb from one direction to the opposite direction, and it is these sudden reversals that produce 40 twisting actions in the lower limb and ligaments therein.

A rheostat (not shown) may be used to vary the speed of the motor 30 and thus vary the intensity of the twisting exercises. These twisting exercises comprise twisting, turning and flexing movements which function in keeping the bones in the lower limb free and the ankle, knee and hip joints active and restore muscular tonus and tendon and ligament activity.

Referring to Figures 1 and 4, it will be noted that there has been provided a hand grip 34 comprising an arcuate member 35 fixed to the plate 12 and having a hand bar 36. The patient may grip the hand bar 36 and by setting the 55

mechanism in motion at a low rate of speed cause oscillatory movements to be imparted to his arm, similar to the oscillatory movements of the lower limb as heretofore described. When the mechanism is caused to operate at high speed, the intensity of the twisting movements imparted to the arm may be increased but under such speed conditions it is essential that the patient should use a glove having a strap (not shown) by means 10 of which the arm may be strapped securely to the hand bar 36. Repetition of these oscillatory movements causes readjustment or correction of misplaced bones of the hand, wrist, elbow and scapula.

15. As shown, the plate 12 has an angular lower portion 37 serving as a support for the shoe 11 and the foot 32 strapped therein. The shoe 11 may be riveted to the vertical portion of the plate 12 into unitary relation with said plate and may 20 also have its upper rear portion riveted to the said angular extension 37 to augment the stability of the device.

It is to be noted that by the term "oscillatory" is meant a to and fro vibratory or swinging motion 25 in an arcuate path and that any curved path defining the motion of my vibratory member is within the scope of my invention.

It is also to be noted that while I have shown one embodiment of mechanism whereby the free 30 end of a human limb may be strapped to a member mounted for oscillatory or arcuate motion and have shown power means for actuating said oscillatory member, this mechanism may be taken as representing any suitable means for performing 35 the same function.

I claim:

1. In an exercising device for causing twisting movements in a human limb while the free and fixed members of said limb are in alignment, the 40 combination with a horizontal spindle having a vertical member mounted thereon intermediate the ends of said member, said member having means for gripping the free extremity of a human

limb, means for oscillating said vertical member to cause rapid and sudden reversals in the twisting of said limb, said means comprising a box-like frame having spaced front and rear walls, said front wall having a circular slot adjacent the upper end of said vertically mounted gripping member, a drive pin secured to said vertical member and extending through said slot, an arm rotatably mounted intermediate its ends on said spindle and having its upper end fixed to said drive pin, a pin fixed to the lower end of said arm and having a link rotatably mounted thereon, a drive shaft rotatably mounted in said rear wall and having a crank arm fixed thereon and facing said front wall, the free end of said crank arm being movably connected to one end of said link and means for rotating said drive shaft.

2. In an exercising device for causing twisting movements in a human limb while the free and fixed members of said limb are in alignment, the 20 combination with a fixed horizontal spindle having a vertical plate member mounted thereon intermediate the ends of said member, said member having means for gripping the free extremity of a human limb, means for oscillating said vertical member to cause rapid and sudden reversals in the twisting of said limb, said means comprising a box-like frame having spaced front and rear walls, said front wall having a circular slot adjacent its upper end, a drive pin secured to said vertical plate member and extending through said slot, an arm rotatably mounted intermediate its ends on said spindle and in free engagement therewith and having its upper end fixed to said drive pin, a pin fixed to the lower end of said arm and having a link rotatably mounted thereon, a drive shaft rotatably mounted in said rear wall and having a crank arm fixed thereon and facing said front wall, the free end of said crank arm being movably connected to one end of said link, and means for rotating said drive shaft.

WILLIAM JOHN NELSON.
